DESIGN FOR AN ARTIFICIAL TOOTH FACING

Leo D. Brubaker, York, Pa., assignor to The Dentists' Supply Company of New York, New York, N. Y., a corporation of New York

Application October 20, 1943, Serial No. 111,427

Term of patent 14 years

(Cl. D24—1)

To all whom it may concern:

Be it known that I, Leo D. Brubaker, a citizen of the United States and a resident of York, county of York, and Commonwealth of Pennsylvania, have invented a new, original, and ornamental Design for an Artificial Tooth Facing, of which the following is a specification, reference being had to the accompanying drawing, forming a part thereof, in which:

Fig. 1 is an elevational view of an artificial tooth facing embodying my new design;

Fig. 2 is a cross-sectional view taken on the line 2—2 of Fig. 1; and

Fig. 3 is a reduced side elevational view thereof.

The dominant features of my design reside in the portions shown in full lines.

I claim:

The ornamental design for an artificial tooth facing, substantially as shown and described.

LEO D. BRUBAKER.
